WILLIAM THOMPSON, OF NEW YORK, AND LESLIE F. BRIGGS, OF BROOKLYN, NEW YORK.

CASH-FARE REGISTER.

Application filed August 27, 1926. Serial No. 131,866.

Our invention relates to cash fare registers.

The object of our invention is to provide a mechanically operated, portable cash fare register of simple construction, particularly applicable for use in transportation vehicles, such as busses, trolley cars and in other instances where a cash fare is deposited.

The novel features of our invention will be more particularly pointed out in the following specification and claims which form a part thereof.

Referring to the drawings,

Fig. 1 is a vertical elevational front view of our construction, shown partly in section.

Fig. 2 is a side sectional view taken on the line 2—2 of Fig. 1.

Fig. 3 is a plan view, partly in section and showing certain parts in dotted lines.

Fig. 4 is a side view of the casing on a reduced scale.

Referring now to the drawings wherein like parts are designated by the same reference characters, we provide a metal casing which may be easily cast of aluminum alloy or other suitable metal and comprising a main portion A and front wall A¹ herein-after further to be referred to as the cover. The main portion is open its entire width and height and on the top side when the cover is removed so that all of the operating parts and mechanism are carried therein being freely accessible permitting of quick and easy inspection, replacement or repair in case of obstruction or injury.

The portion A is provided with a slotted bracket A² formed integral with the back wall by means of which it may be removably supported on a frame or pedestal. The side wall of the top portion A³ is materially reduced in width as illustrated, and an outwardly extending housing A⁴ is formed in the back wall to receive a signal bell B, a portion of which rests within the housing being fastened thereto by a rivet B¹. By forming the housing portion A⁴ on the back wall, the width of the side wall may be reduced and thereby reduces the size and weight of the casing as a whole. The housing is provided with a number of holes or apertures indicated by C to permit the sound of the bell to be more clearly audible.

A laterally extending bracket D¹ is cast integral with the casing and supports an in-

clined coin chute D, the top end of which is in open communication with a coin slot E formed in the upper, offset portion A⁵ of the cover, and an opening is formed in the side of the chute at F directly opposite to a lens G supported by the outwardly bent portion G¹ of said cover and a leaf spring G² fastened on the inside of the said cover as illustrated by Fig. 2 of the drawing.

A laterally extending post H¹ carries a curved arm H on which is mounted a soft metal strip, preferably of copper, and indicated by I, and a striker head I¹ is carried at the free end of the strip. This construction permits the copper strip to be bent to perfect adjustment of the required distance so that the bell will be properly sounded when the mechanism is actuated.

A wire coil spring J is also carried by the post H¹, one end of which abuts the casing and the other end of which is hooked under the arm H to force it upward when released from its lowest operating position. Connected to and suspended from the arm H in pivotal relation is a flat metal strip K, the lower end of which is twisted at K¹ as shown, the purpose of which is to operate the coin check mechanism and counter only when the proper coin is deposited as more fully hereinafter set forth.

L indicates a register preferably of the cyclometer type, such as the well known "Veder" cyclometer, which is carried by a side wall of the casing by means of a suitable bracket construction L¹, the arm M of the cyclometer being connected in pivotal relation with the arm K and K¹ in such manner as to operate the cyclometer to add one count each time the arm K is depressed by a coin. The total count may be observed through a window N formed in the wall of the casing. A rod P is carried by the arm H and extends across the coin chute closely under the cover and over the opening for a short distance at one side thereof being so positioned that a nickel forced through the slot E will bear against the rod P and depress the same a distance sufficient to operate the cyclometer counter, and when the nickel snaps through into the chute D, the spring J throws the arm H upward causing the striker to ring the signal bell. The coin then rolls down through the chute to the position opposite the lens G where it is held by the curved portion F of the arm K which ex-

tends through a slot in the top of the chute to control the passage. When the next nickel is forced through the slot E, the arm K moves downward and its lower end slides to the lower end of the chute and the nickel formerly deposited and held for inspection is lowered to a point where an opening R formed in the side and bottom of the chute permits the coin to fall from the chute to an inclined plate S. The plate S is provided with a depending wing S¹ from which a guide rod S² extends and is supported by a bracket T. A helical spring T¹ holds the plate S normally in its lower position but by pressing on the wing S¹ the plate slides back and the coins thereon drop over its lower edge into the hand of the operator of the vehicle when the hand is inserted into the bottom of the casing through an opening A⁶. A glass plate U permits the coins to be seen within the casing.

Means for closing the coin slot E, illustrated in Fig. 3 comprises a thin metal plate V carried on the under side of the cover in pivotal relation thereto by a stud V¹, the flat portion V² being adapted to rest under the slot E over the upper end of the coin chute. The opposite end is bent over to form an abutment surface at V³ against which a removable pin W may be pressed to move the plate to its open position. A small spring may be used to hold the plate in closed position.

The top wall portion of the cover A⁷ serves a very useful function to guide the hand when depositing a coin and also serves as a sign space on which the required fare is set forth. To prevent a coin from being projected back out of the coin slot in case it is released by the depositor before its greatest diameter has passed below the cross pin P, the top end of the coin chute is curved to form a small overhanging portion at a point X which causes a quick release of the coin after the greater diameter thereof has passed the cross pin P and prevents it from slipping backward. A mirror Y supported by a double hinge Y¹ is mounted on the cover adjacent the lens in swinging, adjustable relation thereto which permits the coin held in the chute to be observed by the operator of the vehicle while sitting in the act of steering.

The free end of the lever extends through a hole formed in an offset portion K² of the arm K to permit it to swing toward the side wall of the casing, and a helical spring K⁴ carried by the lever abuts the said offset portion and cooperates with the spring J in moving the arm H.

The drawings are made on a scale of substantially one half the actual size but the device may be made smaller in size if desired. By eliminating all electrical means we avoid many parts which get out of order

and cause trouble and at the same time reduce the cost of its manufacture. The operation is as follows:

The pin W is inserted to move the lever V and uncover the passage in the coin chute. A nickel is forced into the coin slot and presses the cross pin P downward in a circular movement, causing the arm H to move downward, its lower end being guided by the inner walls of the coin chute swings toward the left side of the casing and follows the incline of the top thereof to its lower end. As the coin passes the cross pin, the arm H swings upward causing the bell to be struck by the striker and at the same time the lower end of the arm K moves upward and catches the coin and holds it in position opposite the lens for observation. At the same time the movements of the arm K operates the lever of the counter. The next nickel deposited in the coin chute repeats the operation just described and also permits the first coin to drop from the chute during the short period of time that the coin is being forced past the cross pin P. An electric light bulb Z may be placed adjacent the coin in the casing to illuminate the same if desired and the mirror set to reflect the light adds greatly to the use of the device.

Having thus described our invention, what we claim as new and desire to secure by Letters Patent of the U. S. is:—

1. A cash fare register comprising a casing having a back and two side walls and a top portion of reduced width, and a cover comprising a front wall having an off-set top wall formed with a plane surface, said top wall having a coin slot formed therein, a coin chute supported in the casing substantially in parallel relation to the front wall, the top end of said chute communicating with the coin slot in said cover, mechanism comprising a counter supported in the casing, means whereby said mechanism will automatically operate to register the coin inserted into said coin chute and means for releasing said coin from said casing, said cover being free of the operating mechanism and removable from said back and side walls and from said operating mechanism without disturbing said mechanism.

2. A cash fare register comprising a casing having a back and two side walls and a top portion of reduced width, and a cover comprising a front wall and a top wall, said top wall having a coin slot formed therein, a coin chute supported in the casing substantially in parallel relation to the front wall, the top end of said chute communicating with the coin slot in said cover, mechanism comprising a counter supported in the casing and a signal bell in the upper reduced portion thereof, means whereby said mechanism and signal bell will operate automatically.

5 cally when a proper coin is inserted into said coin chute and register said coin, said cover being free of the operating mechanism and removable from said back and side walls and from said operating mechanism without disturbing the said mechanism.

10 3. A cash fare register comprising a casing having a back and two side walls and a top portion of reduced width, and a cover comprising a front wall and a top wall, said top wall having a coin slot formed therein, a coin chute supported in the casing substantially in parallel relation to the front wall, the top end of said chute communicating

15 with the coin slot in said cover, means for holding a coin in said chute, a magnifying lens in said front wall adjacent said chute through which the deposited coin may be observed, mechanism comprising a counter and 20 signal bell supported in said casing and arranged to automatically operate when a proper coin is inserted into said coin chute and register said coin, while releasing the coin held in the chute.

25 4. A cash fare register comprising a casing having a back wall and two side walls, said back wall extending above the side walls for a predetermined distance and having an outwardly extending portion formed 30 therein and a signal bell therein, and a cover portion comprising a front wall and an offset flat top wall, said top wall having a coin slot formed in the flat top thereof, a coin chute supported in the casing, the top end of said chute communicating with the coin slot in 35 said cover, mechanism comprising a counter supported in the casing, means whereby said mechanism will automatically operate when a proper coin is inserted into said coin 40 chute to register said coin and manually operated means for releasing said coin from said casing, said cover being removable from said back and side walls and from said operating mechanism without disturbing said mechanism.

45 5. A cash fare register comprising a casing having a cover provided with a coin slot in the top thereof, an inclined coin chute supported in the casing, an arm carried by the casing in swinging relation thereto, a striker carried by said arm, a bell, a flat metal strip hinged to said arm, the lower end of said strip being movable in said coin chute, a counter operated by said strip, a pin carried by said arm and extending across the upper end of the coin chute and under said coin slot and adapted to be moved by a coin to operate the register and means carried on the inner side of the casing for returning said strip to its normal position.

60 6. A cash fare register comprising a casing having a cover provided with a coin slot in the top thereof, an inclined coin chute supported in the casing, an arm carried by

65 the casing in swinging relation thereto, a striker carried by said arm, a bell, a flat metal strip hinged to said arm, the lower end of which is movable in said coin chute, an inclined plate located below said coin chute and movable to permit a coin to slide 70 from the inclined surface thereof to an outlet, a counter operated by said strip, a pin carried by said arm and extending across the upper end of the coin chute and under said coin slot and adapted to be moved 75 by a coin to operate the register and means for returning said strip to its normal position.

7. A cash fare register comprising a casing having a cover provided with a coin slot 80 in the top thereof, an inclined coin chute supported in the casing, an arm carried by the casing in swinging relation thereto, a signal within the said casing, a flat metal strip hinged to said arm, the lower end 85 of which is movable in said coin chute, an inclined plate located at the bottom of the coin chute and movable inwardly of the casing, said casing having a hand opening between its bottom and the inclined plate 90 whereby the deposited coins may be removed, a counter operable by the strip, a pin carried by said arm and extending across the upper end of the coin chute and under the coin slot and adapted to be moved by a 95 coin to operate the register and means for restoring said strip to its normal position.

8. A cash fare register comprising a casing, a detachable cover for said casing comprising a front wall and a top wall, said top 100 wall being provided with a coin slot therein, a coin chute within the casing communicating with the coin slot, a bent strip extending into the chute, means for actuating said strip, said strip being adapted to retain a 105 coin and releasable when a coin is forced through the coin slot, and a register simultaneously operable with the strip.

9. A cash fare register comprising a casing having a supporting bracket, a detachable cover for said casing comprising a front wall and a top wall, said top wall being provided with a coin slot, a coin chute within the casing communicating with the coin slot, a removable lens carried by the cover 110 whereby the interior of the coin chute may be observed, a bent strip extending into the coin chute, means for actuating the said strip, a register cooperating with the said strip and operable therewith when the proper coin is forced through the coin slot, a sliding plate at the bottom of the coin chute, said casing having a hand opening below the sliding plate whereby the same may be moved 115 inwardly of the casing when the hand is inserted permitting the deposited coins to be removed.

10. The combination with a closed recep-

tacle of a coin chute, a coin registering mechanism having an actuating element interposed in the path of the coin to operate said registering mechanism, said mechanism comprising a movable retaining strip extending into the coin chute at its lower end and serving to hold the coin after it has operated the

register, and operating to release the coin when a following coin again operates the register.

10

In testimony whereof we have affixed our signatures.
